UNITED STATES PATENT OFFICE.

CHARLES B. YOUNG AND CHARLES J. CASPAR, OF PITTSBURGH, PENNSYLVANIA, AS
SIGNORS TO PITTSBURGH PLATE GLASS COMPANY, A CORPORATION OF PENN-
SYLVANIA.

STORE-FRONT CONSTRUCTION.

Application filed April 10, 1925. Serial No. 22,066.

To all whom it may concern:

Be it known that we, CHARLES B. YOUNG and CHARLES J. CASPAR, citizens of the United States, and residents of Pittsburgh, in the county of Allegheny and State of Pennsylvania, have made a new and useful Invention in a Store-Front Construction, of which the following is a specification.

The invention relates to store front constructions. It has for its principal object the provision of an improved construction which permits of the setting of the glass from the front in such manner that there is no danger of breaking the glass and with a minimum amount of effort on the part of the workmen. It has for its further object the provision of an improved cover plate construction in which the number of holding screws is reduced to a minimum and which is held very securely, but which at the same time, presents none of the difficulties as to removal after a long period of time, such as are present with certain of the so-called screwless types of cover plates. One embodiment of the invention is illustrated in the accompanying drawings wherein:

Figure 1 is a front view of the assembled construction with portions of the glass and cover strip broken away to more clearly disclose the construction. Fig. 2 is a perspective view showing the construction of one of the clamps with the glass and cover strip removed. And Fig. 3 is a section on the line III—III of Fig. 1.

Referring to the drawings, the members 1 and 2 are parts of the window framing in which the glass plate 3 is seated, the part 1 constituting an inwardly projecting ledge in opposition to the rear face of the glass and the part 2 constituting a laterally extending ledge in opposition to the edge of the glass sheet. The glass sheet is supported by means of the usual wood blocks (not shown), the pressure of the holding devices as later described not being sufficient to support the weight of the glass. The two ledges 1 and 2 are protected by means of metal sheathing of the angular cross section indicated in Fig. 3, the upright portion 4 being referred to as the back strip and the lateral portion 5 being referred to as the base strip as these parts might be separate members and the part 4 might be dispensed with, although the preferred and usual arrangement is to

employ the construction just as illustrated so as to give a maximum amount of protection to the wood members 1 and 2.

At its outer edge, the bottom strip 5 is provided with a flange 6 spaced away from the ledge 2 to provide a recess for the edge of the cover strip as later described. Spaced at intervals along the base strip are the angular brackets or clips 7, each having a flange 8 in opposition to the back strip and a flange 9, the outer portion of which is offset, as indicated in Figs. 2 and 3 to provide a space for the lower ends of the screws 10, the extreme outer edges of the flanges 9 being supported upon the flanges 6 of the base strip 5. The flanges 8 of the brackets or clips are clamped against the back strip 4 by means of the wood screws 11, although this might be accomplished by use of machine screws which do not extend into the ledge 1. However, the arrangement shown is preferred, as the screws 11 perform the double function of holding the sheathing, comprising the members 4 and 5 in position and of clamping the brackets 7 in position.

Upon each of the brackets or clips 7 is mounted an angle clamp or bracket 12, such bracket comprising a clamping flange 13 and the laterally extending flange 14, which rests upon the bracket 7. The clamp is preferably provided with a slotted portion 15 lying in the flange 14 and a slotted portion 16 lying in the flange 13, the slot 16 being wide enough to permit the head of the holding screw 10 to slide therethrough, thus providing in effect a bayonet joint, permitting application and removal of the clamp without removing the screw 10. The opposing faces of the flanges may be, and preferably are, roughened, so that when the screw 10 is tightened, there is less danger of the clamp slipping. As heretofore referred to, the spacing of the flange 9 away from the cover strip 5 provides room for the lower end of the screw 10 so that it may be tightened without coming into contact with the base strip.

The upper edge of the clamping flange 13 is turned back upon itself as indicated at 17 and provided with a threaded perforation 18. The cover strip 19, preferably of sheet copper, is formed at one edge with the flange 19 adapted to fit beneath the flange 6, and at its other edge, is turned laterally at 20 so as to fit over the clamps and entirely

cover them. The cover strip is secured in position at its upper edge by means of the screws 21.

In setting the glass 3, it is first placed in position in the sheathing 4, 5 supported at suitable intervals by small wood blocks. The clamps 12 are then put into position and pressed up against the glass and the screws 10 tightened. This procedure prevents any undue pressure being applied to the glass by the clamps 12, since the application of the screws 10 does not tighten the clamps. There is, therefore, no danger of breaking the glass from this cause, such as sometimes occurs with a clamp arranged so that tightening of the screw holding it forces the clamp against the glass. The cover strip is then applied by hooking its flange 19 beneath the flange 16 and applying its upper edge over the clamps as indicated in Fig. 3, after which the screws 21 are put in place. The labor of applying the cover strip is thus relatively slight, as screws need to be applied only at one edge. The cover strip is also easily removed after a long period of service, since there is no difficulty in removing the screws 21, after which the upper edge of the cover strip can be sprung back permitting a grip upon the strip either by the hands of the operator or by a tool such that the flange 19 may be loosened without difficulty, even though it has tightened in position due to corrosion or other causes incident to the passage of time. The glazing of the window can be accomplished by one man working from the outside, as no cooperation is required from the inside of the glass as is the case in many forms of setting. Other advantages incident to the cheapness and simplicity of the construction and the ease with which it may be applied and removed from position and its extreme safety will be readily apparent to those skilled in the art.

45 What we claim is:

1. In a store front construction, including a window framing and a glass sheet mounted therein, a metal base strip secured to the framing and having its outer edge spaced away from the framing to provide a holding flange, holding brackets mounted at spaced intervals along the base strip and secured rigidly in position, clamping brackets mounted upon the holding brackets and each comprising an inwardly extending clamping flange in opposition to the face of the glass plate and a laterally extending flange engaging one of said holding brackets, screw means extending through said laterally extending flanges and into the holding brackets for securing the clamping brackets in position, a cover strip having an inwardly turned flange at one edge fitting beneath said flange on the base strip and at its other edge overlapping and covering the clamp-

ing flanges of the clamping brackets, and screw means extending through said other edge of the cover strip and into the clamping edges of the clamping brackets.

2. In a store front construction, including 70 a window framing and a glass sheet mounted therein, a metal base strip secured to the framing and having its outer edge spaced away from the framing to provide a holding flange, holding brackets mounted 75 at spaced intervals along the base strip and secured rigidly in position, clamping brackets mounted upon the holding brackets and each comprising an inwardly extending clamping flange in opposition to the face of 80 the glass plate, having its free edge turned back upon itself and a laterally extending flange engaging one of said holding brackets, screws releasably clamping said laterally extending flanges to said holding brackets, 85 a cover strip having an inwardly turned flange at one edge fitting beneath said flange on the base strip and at its other edge overlapping and covering the clamping flanges of the clamping brackets, and screws 90 extending through said other edge of the cover strip and into the turned back edges of the clamping brackets.

3. In combination, a store front construction including a window framing having an 95 inwardly extending ledge and a laterally extending ledge and a glass seated in the framing with its rear face in opposition to said inwardly extending ledge and its edge in opposition to said laterally extending 100 ledge, a metal base strip seated upon said laterally extending ledge and having its outer edge spaced away from the ledge to provide a holding flange, angle brackets seated at spaced intervals along the base 105 strip each having one flange thereof in opposition to said inwardly extending ledge and the other flange in opposition to the base strip, screw means extending through the first mentioned flange of the bracket 110 for clamping the bracket in fixed position relative to said ledges, an angle clamp mounted upon each bracket with one flange in opposition to the front face of the glass, screw means for securing the clamps to the 115 brackets, a cover strip having an inwardly turned flange at one edge fitting beneath said flange on the base strip and at its other edge overlapping the clamping flanges of the angle clamps, and screw means extending through said other edge of the cover strip and into said clamping flanges of the angle clamps.

4. In combination, a store front construction including a window framing having an 120 inwardly extending ledge and a laterally extending ledge and a glass seated in the framing with its rear face in opposition to said inwardly extending ledge and its edge in opposition to said laterally extending 125 ledge,

- ledge, a metal base strip seated upon said laterally extending ledge and having its outer edge spaced away from the ledge to provide a holding flange, angle brackets seated at spaced intervals along the base strip each having one flange thereof in opposition to said inwardly extending ledge and the other flange in opposition to the base strip, screw means extending through 5 the first mentioned flange of the bracket for clamping the bracket in fixed position relative to said ledges, an angle clamp mounted upon each bracket with one flange in opposition thereto and the other comprising a 10 clamping flange in opposition to the front face of the glass, screw and slot connections between the clamps and the brackets to permit the adjustment of the clamps toward and from the glass, a cover strip having an inwardly turned flange at one edge fitting beneath said flange on the base strip and at its other edge overlapping the clamping flanges of the angle clamps, and screw means extending through 15 said other edge of the cover strip and into said clamping flanges of the angle clamps.
5. In combination, a store front construction, including a window framing having an inwardly extending ledge and a laterally extending ledge and a glass seated in the framing with its rear face in opposition to said inwardly extending ledge and its edge in opposition to said laterally extending ledge, a metal base strip seated upon 20 said laterally extending ledge and having its outer edge spaced away from the ledge to provide a holding flange, angle clamps mounted at spaced intervals along the base strip, each having one flange in opposition 25 to the base and the other comprising a clamping flange in opposition to the front face of the glass, screw means extending through the first mentioned flange of the 30
- clamp for securing the clamp in fixed position with relation to the base strip, a cover strip having an inwardly turned flange at one edge fitting beneath said flange on the base strip and at its other edge overlapping the clamping flanges of the angle clamps, and screw means extending through 35 said other edge of the cover strip and into said clamping flanges of the angle clamps.
6. In combination, a store front construction, including a window framing having an inwardly extending ledge and a laterally extending ledge and a glass seated in the framing with its rear face in opposition to said inwardly extending ledge and its edge in opposition to said laterally extending ledge, anchoring means seated in fixed 40 position upon said laterally extending ledge and having flange holding means spaced away from the ledge, angle clamps mounted at spaced intervals along the laterally extending ledge, each having one flange in 45 opposition to the laterally extending ledge and the other comprising a clamping flange in opposition to the front face of the glass, screw means extending through the first mentioned flange of the clamp for securing 50 the clamp in fixed relation with respect to the laterally extending ledge, a cover strip having an inwardly turned flange at one edge fitting beneath said flange holding means on the anchoring means and at its 55 other edge overlapping the clamping flanges of the angle clamps, and screw means extending through said other edge of the cover strip and into said clamping flanges of said 60 angle clamps.
- In testimony whereof, we have hereunto 65 subscribed our names this 3rd day of April, 1925.
- CHARLES B. YOUNG.
CHAS. J. CASPAR.
